DESIGN FOR AN ARTICLE OF MANUFACTURE.

Specification for Design.

Patented Apr. 15, 1919.

Application filed November 7, 1918. Serial No. 261,556. Term of patent 3½ years.

To all whom it may concern:

Be it known that I, EDITH C. BLUM, a citizen of the United States of America, and a resident of the borough of Manhattan, city and State of New York, have invented a new, original, and ornamental Design for an Article of Manufacture, of which the following is a specification, reference being had to the accompanying drawing, showing my design.

The drawing shows a face view of a portion of a textile fabric bearing my design.

While I have shown my design embodied in a textile fabric, I want it to be understood that the application of the design is not limited to textile fabrics, as it may obviously be embodied in various other articles of manufacture.

The color indicated by way of example in the drawing by the shading, may be varied without departing from my invention.

The design is intended to be repeated lengthwise and transversely of the fabric.

The essence of my invention resides in the general appearance of the design, substantially as shown and described. It is to be understood that my claim includes all substantial equivalents of my design as shown and described.

I claim:

The ornamental design for an article of manufacture substantially as shown and described.

EDITH C. BLUM.
